Patented June 26, 1973

227,439

HOLDER FOR PAINT CANS ON LADDERS

Alvin O. Brothers, 2001 E. Franklin St.,
Evansville, Ind. 47711

Filed July 26, 1971, Ser. No. 166,330

Term of patent 14 years

Int. Cl. D8—08

U.S. Cl. D8—233

FIG. 1

FIG. 2

FIG. 3

FIG. 4

FIG. 1 is a view in side elevation of the holder for paint cans on ladders comprising the invention, where the opposite side is a mirror image thereof;

FIG. 2 is a top plan view of the claimed design;

FIG. 3 is a view in front elevation of the claimed design; and,

FIG. 4 is a view in rear elevation of the claimed design.

I claim:

The ornamental design for a holder for paint cans on ladders, as shown and described.
